(57) CLAIM

The ornamental design for a corn holder, as shown and described.

DESCRIPTION

FIG. 1 is a side perspective view of a corn holder showing an exemplary embodiment of our new design;

FIG. 2 is another side perspective view of the corn holder of FIG. 1;

FIG. 3 is a left side view of the corn holder of FIG. 1;

FIG. 4 is a right side view of the corn holder of FIG. 1;

FIG. 5 is a back view of the corn holder of FIG. 1;

FIG. 6 is a front view of the corn holder of FIG. 1; and

FIG. 7 is a top view of the corn holder of FIG. 1; and

FIG. 8 is a bottom view of the corn holder of FIG. 1; and,

FIG. 9 is a side perspective view thereof, with another corn holder interlocked and shown in broken lines for illustrative purposes only and forming no part of the claimed design.
